SKI BOOT

Alden B. Hanson and Chris A. Hanson, Boulder, Colo.,
assignors to Hanson Industries Inc., Boulder, Colo.

Filed July 17, 1972, Ser. No. 272,688

Term of patent 14 years

Int. Cl. D2—04

U.S. Cl. D2—276

FIG. 1

FIG. 2

FIG. 3

FIG. 4

FIG. 7

FIG. 5

FIG. 6

FIG. 1 is a side elevational view of a ski boot showing our new design;

FIG. 2 is an elevational view of the other side thereof;

FIG. 3 is a rear elevational view;

FIG. 4 is a front elevational view;

FIG. 5 is a top plan view;

FIG. 6 is a bottom plan view; and

FIG. 7 is a side elevational view of a second embodiment of the design of FIG. 1 differing thereover only in that it has one buckle fastener.

We claim:

The ornamental design for a ski boot, as shown and described.
